US00D895411S

(12) **United States Design Patent** (10) Patent No.: **US D895,411 S**
Camilleri et al. (45) Date of Patent: ** Sep. 8, 2020

(54) **SCREW FASTENER**

(71) Applicant: **Illinois Tool Works Inc.**, Glenview, IL (US)

(72) Inventors: **Mark Anthony Camilleri**, Oatley (AU); **Bryan Hugh Marshall**, Turramurra (AU)

(73) Assignee: **Illinois Tool Works Inc.**, Glenview, IL (US)

(**) Term: **15 Years**

(21) Appl. No.: **29/659,632**

(22) Filed: **Aug. 10, 2018**

Related U.S. Application Data

(63) Continuation of application No. 29/594,366, filed on Feb. 17, 2017, now Pat. No. Des. 828,148.

CLAIM

The ornamental design for a screw fastener, as shown and described.

DESCRIPTION

FIG. 1 is a bottom perspective view of a screw fastener of our new design.

FIG. 2 is a top perspective view of the screw fastener of FIG. 1.

FIG. 3 is a front view of the screw fastener of FIG. 1.

FIG. 4 is a left side view of the screw fastener of FIG. 1.

FIG. 5 is a right side view of the screw fastener of FIG. 1.

FIG. 6 is a top plan view of the screw fastener of FIG. 1; and,

FIG. 7 is a bottom plan view of the screw fastener of FIG. 1.

The broken lines in the drawings illustrate portions of the screw fastener and form no part of the claimed design.

1 Claim, 7 Drawing Sheets
